UNITED STATES PATENT OFFICE.

JULIEN WARNANT-CRÉON, OF HOIGNÉE-CHERATTE, NEAR LIEGE, BELGIUM.

AUTOMATIC RIFLE.

No. 908,631.

Specification of Letters Patent.

Patented Jan. 5, 1909.

Application filed November 4, 1907. Serial No. 409,710.

To all whom it may concern:

Be it known that I, JULIEN WARNANT-CRÉON, gun-maker, subject of the King of Belgium, residing at Hoignée-Cheratte, near Liege, Belgium, have invented certain new and useful Improvements in Automatic Rifles; and I hereby declare the following to be a full, clear, and exact description of the same, such as will enable others skilled in the art to which it appertains to make and use the invention.

The present invention relates to an automatic rifle constructed so as to provide an effective fastening, that is to say, a positive locking of the breech-bolt to the arm with the objects of preventing the escape of the gases and imparting to the projectile, greater power of penetration.

The improved rifle is of simple construction and easy to disassemble.

Figure 1 of the annexed drawing represents a longitudinal section of the improved rifle, showing the firing mechanism cocked and the bolt thrown back. Fig. 2 is a similar section but shows the parts in the positions they assume when the trigger is pulled and the hammer is released. Fig. 3 is a transverse section on A—B (Fig. 2). Fig. 4 is a horizontal section on C—D (Fig. 2), showing the bolt in plan. Fig. 5 is a part longitudinal section through the breech-casing and showing the left side of the bolt in elevation. Fig. 6 represents an elevation of the left-hand side of the rifle. Fig. 7 shows a part section on E F (Fig. 2) the safety device being in engagement with the trigger.

The cylindrical breech-bolt 1 is inclosed within a casing 2, which is solid with the barrel 3, and is carried and guided by the frame or shoe 4, wherein also the firing mechanism of the rifle is fitted. The bolt contains the firing pin 5, guided by the screw 6 and the spring 7 whose tendency is to force the said firing pin rearwardly.

The magazine 8 is located in front of the trigger-guard which forms part of the shoe or frame 4, and it is secured in position by the nose 9 of a pivoted catch-lever 10 which engages in a notch in the magazine and which can be disengaged by operating the pusher 11 at the end of the catch lever 10. The firing and locking mechanism consists of a hammer 12 mounted on an axis 13 carried by the frame or shoe 4, to which is also fixed the firing spring 14. The trigger

15 is pivoted on its pin 16 and is maintained in its forward position by a spring 17, which is located in a recess of the said trigger and which tends also to engage the sear 18 with a notch in the hammer 12. This trigger 15 carries at the back a part 19 forming a releasing member, and through the medium of which the trigger 15 engages with the sear 18.

The bolt 1 is provided with a lateral recess 20 which is engaged by the short arm of the cranked or bent end of a sliding rod or limb 21 which is guided laterally in the frame 4 and whose front part is surrounded by the re-action spring 22. This spring 22 bears at the rear end against the frame of the rifle, and at the front against a washer or nut 23 which is fixed to the slide-rod 21, so that the said rod and the nut 23, which is connected to it, are normally maintained in a forward position. The sliding limb 21 and the spring 22 are located in a casing 24 which is arranged under the barrel, and wherein there is also mounted, a sliding cross-piece 25, which traverses within slots 26 formed through side walls of the casing 24. This cross-piece carries lateral projections 27, which cover the slots 26 and are adapted to serve as pushers for the manipulation of the breech-bolt. The travel of this slide 25, on which the front extremity of the rod 21 bears is limited at the front by the screw or pin 28.

The pivot 13 of the hammer 12 is provided with a squared part on which the hammer is mounted while the ends of the said pivot have their bearing in the side walls of the breech casing 2. This pivot 13 carries at one of its ends, and outside the breech 2, a lever 29, which the firer operates for cocking the hammer for the first shot, as will be described hereafter.

The locking of the bolt 1 is effected by a limb 30 pivoted (either in the breech-casing 2 or on the shoe or frame 4,) upon the pin 31, which passes through the front end of the said limb, while its rear end rests on the front face of the hammer 12, above the pivot 13. This limb 30 has near the top, a nose 32 which enters into engagement with the notch 33 of bolt 1 when the parts of the rifle are in their fired positions, and the hammer is released (Fig. 2).

To cock the rifle, before firing the first shot, the shooter brings the hammer 12 into engagement with the sear by operating the

lever 29 so as to turn this latter from the position represented in dotted lines Fig. 6, into that shown in full lines. By then drawing the slide 25 rearwardly, the bolt 1 is brought through the medium of the sliding rod 21, into the position represented in Fig. 1, after which the said slide is released and both the bolt and the rod are restored to their normal position by the spring 22. By this forward movement of the bolt a cartridge is pushed out of the magazine 8 and introduced into the chamber of the barrel 3. If the trigger 15 which is pivoted on its pin 16 is then pressed, the piece 19 will lift the rear arm of the sear 18, whose front nose will be disengaged from the hammer 12. This latter then strikes the firing pin 5 and fires the cartridge in the chamber of the barrel 3. At the same time the locking limb 30 is turned from the position shown in Fig. 1 to that of Fig. 2, where the projection 32 is within the notch 33 of the firing bolt. The force of the explosion tends to turn the locking limb downwards about its pivot 31, which causes a certain pressure to be exerted on the hammer 12, in the direction of the hammer-pivot, or approximately in that direction. The result is that the hammer is temporarily locked or wedged in the fired position (Fig. 2) so as to momentarily resist or oppose the rearward movement of the recoiling breech-bolt and prevent the escape of the powder gases at the breech until the bullet has left the barrel and thus a great power of penetration is imparted to the projectile.

As the force of the explosion overcomes the resistance caused by the above-described action of the locking limb on the hammer, said limb and hammer are automatically returned to the positions shown in Fig. 1. That is, the hammer is automatically re-cocked and the locking limb 30 left in position to be again swung upward, by the hammer, when the trigger is pulled. When the sear has been lifted by the jointed piece 19 at the rear end of the trigger 15, the nose 34 of this piece 19 meets the end of the frame or shoe 4, of the rifle, so that it turns rearwards, and disengages itself from the sear 18 for the purpose of again engaging below this latter under the action of the small spring 35 immediately the trigger 15 has been released by the firer, and when the front nose of the sear 18 is reengaged in the notch of the hammer 12. Under the effect of the recoil the bolt 1 is driven rearwardly, which causes, in the well known manner, the extraction and the ejection of the empty cartridge, the cocking of the hammer, and the introduction of a fresh cartridge in the chamber of the barrel 3. The same movements are then repeated.

65 As long as the cocking is effected by the

recoil and the shooter does not operate the slide 25, this latter remains immovable at the front of the casing 24. In the example represented, the mechanism is completed by a safety device arranged under the shoe 4 and behind the trigger guard. It consists of a sliding piece, provided with a head 36 which the firer operates, and is forked at the front to engage above the sear-releasing member 19 and to thus lock the trigger 15 when the arm is put into its safety position (Fig. 7).

It is obvious that this mechanism is applicable to other arms of the same type to that shown in the drawings and that the rifle above described and represented in the accompanying drawings can undergo, in its details various constructive modifications without departing from the nature of the invention.

Having fully described my invention, what I desire to claim and secure by Letters Patent is:—

1. In an automatic firearm, the combination with a non-recoiling barrel, a reciprocating breech bolt, and firing mechanism, of an adjustable locking member adapted to be shifted by the hammer of the firing mechanism to engage the breech bolt and momentarily prevent recoil thereof when the gun is fired.

2. In an automatic firearm, the combination with a non-recoiling barrel, a reciprocating breech bolt, and firing mechanism, of an adjustable locking member adapted to be shifted by the hammer of the firing mechanism to engage the breech bolt so that when the gun is fired the force of the recoil will be directed against the relatively stationary support of the firing hammer and rearward movement of the breech bolt momentarily checked.

3. In an automatic fire arm, the combination with a barrel, reciprocating breech bolt, and firing mechanism, including a swinging hammer, of means between the hammer and breech bolt for transmitting the rearward pressure produced by firing the gun to the hammer and momentarily checking the recoil of the breech bolt when the gun is fired.

4. In an automatic fire arm, the combination with a barrel, reciprocating breech bolt and firing mechanism including a hammer, of a pivotally mounted locking member adapted to be adjusted by the hammer, as the gun is fired, to engage the breech bolt and momentarily prevent recoil of the bolt.

5. In an automatic fire arm, the combination with a barrel, reciprocating breech bolt and firing mechanism including a swinging hammer, of a pivotally mounted locking member arranged between the hammer and breech bolt and contacting with the hammer, whereby it will be rocked to engage the breech bolt as the hammer moves in firing

the gun, the locking member coöperating with the hammer to momentarily prevent recoil of the breech bolt when the gun is fired.

- 5 6. In an automatic firearm, the combination with a non-recoiling barrel, a reciprocating breech bolt, and firing mechanism including a hammer, of means coacting with the hammer and adapted to be shifted thereby to prevent rearward movement of the breech bolt when the gun is fired, means for moving the hammer to release the lock holding the bolt in its forward position, means for manually adjusting the breech bolt rearwardly, and a spring acting to return the breech bolt to its forward position.
7. In an automatic fire arm, the combination with a barrel, a reciprocating breech bolt, and firing mechanism including a swinging hammer, of means coacting with the hammer and acting to prevent rearward movement of the bolt, a rod connected with the breech bolt and extending forwardly thereof, a spring acting to hold the bolt and rod in their forward position, and means for

swinging the hammer rearwardly to release the lock holding the bolt in its forward position.

8. In an automatic fire arm, the combination with a barrel, a reciprocating breech bolt, and firing mechanism including a swinging hammer, of means coacting with the hammer and acting to prevent rearward movement of the bolt, a rod connected with the breech bolt and extending forwardly thereof, a spring acting to hold the bolt and rod in their forward position, and a lever connected with the hammer and adapted to rock the same rearwardly to release the lock holding the breech bolt in its forward position to permit said rod to readily shift the bolt rearwardly.

In testimony whereof I have signed my name to this specification in the presence of two subscribing witnesses.

JULIEN WARNANT-CRÉON.
